UNITED STATES PATENT OFFICE

WILLIAM E. NELSON, OF MINNEAPOLIS, MINNESOTA

INSULATING UNIT

Application filed September 24, 1927. Serial No. 221,771.

This invention relates to new and useful improvements in insulating units or slabs particularly adapted for use in refrigerators and other apparatus where such units may be used to prevent the conduction of heat through the walls thereof. It is an improvement over the form shown in my pending application, Serial No. 218,230, filed September 8th, 1927.

An object of the present invention is to provide an insulating unit or slab which may be manufactured at a minimum cost, and comprises a suitable non-conductive, dry, fibrous filler, having its opposite ends enclosed in suitable waterproof end caps, and the central portion of said filler being enclosed in an open-ended casing having its ends overlapping the walls of said end caps and secured thereto by a suitable water-proof material, such as tar or asphalt, whereby the joints between the casing sheet and the end caps will be sealed against moisture.

A further object of the invention is to provide an insulating unit or slab comprising a plurality of dry fibrous filler sheets stacked one upon the other to provide a nonconductive body, and water-proof caps of flexible material enclosing the opposite ends of said body, and a casing also of water-proof material disposed about the central portion of said body with its opposite edges overlapping the walls of said end caps, and preferably, but not necessarily, secured thereto by a suitable water-proof material, to prevent the entrance of moisture into said body.

Other objects of the invention will appear from the following description and accompanying drawings and will be pointed out in the annexed claims.

In the accompanying drawings, there has been disclosed a structure designed to carry out the various objects of the invention, but it is to be understood that the invention is not confined to the exact features shown as various changes may be made within the scope of the claims which follow.

In the accompanying drawings forming part of this specification;

Figure 1 is a perspective view showing the filler sheets arranged in superposed relation and the end caps fitted over the ends thereof;

Figure 2 is a view similar to Figure 1, showing the casing sheet wrapped about the filler sheets and overlapping the walls of the end caps;

Figure 3 is a view showing the completed unit;

Figure 4 is a sectional view on the line 4—4 of Figure 3;

Figure 5 is a modified form showing the end caps fitted over the opposite edges of the casing sheet; and

Figure 6 is another modification showing the use of channel-shaped caps instead of the form shown in Figure 1.

The novel insulating unit or slab featured in this invention comprises a non-conductive dry fibrous body or filler, preferably consisting of a plurality of felted sheets 2, arranged in superposed abutting relation, as shown in Figure 1. Water-proof end caps 3, preferably formed of flexible material, are mounted upon the opposite ends of the body or filler as shown in Figure 1 and enclose the ends of the filler sheets 2 to protect them against moisture.

A water-proof casing sheet 4 is wrapped about the filler sheets 2 with its opposite edges 5 and 6 overlapping the side walls 7 and the end walls 8 of the end caps 3, as shown in Figure 2. A coating 9 of asphalt or tar is applied to the outer surfaces of the walls 7 and 8 of the end caps 3 and also to one end of the casing sheet 4, so that when the latter is engaged with the end caps 3 and the ends thereof are overlapped, as shown in Figure 2, the casing sheet will be securely united to the end caps 3, thus providing a water-proof casing for the filler sheets. If desired, the opposite edges of the casing sheet 4 may be coated with a suitable water-proof material, such as tar or asphalt to further render the unit waterproof.

Figure 3 illustrates the unit in its completed form. The shaded portions 10 indicate a coating of tar or asphalt, which may be applied to the joints exteriorly of the unit to further prevent the entrance of moisture into the filler sheets.

Figure 5 illustrates a modified form where-

in the casing sheet 4 is first wrapped around the filler sheets, and its overlapping ends united, after which the end caps 11 are fitted over the ends thereof and secured thereto by a 5 coating 12 of tar or asphalt to render the casing moisture-proof.

Figure 6 illustrates another modified form wherein channel-shaped caps 13 are fitted over the side edges of the unit and cooperate 10 with the end caps 3 to bind the filler sheets together as a unit. A coating of tar or asphalt may then be applied to the outer surfaces of the filler sheets and caps 3 and 13 to prevent the entrance of moisture into the unit.

15 The caps 3, 11, and 13 are preferably constructed of water-proof material such as building paper but, if desired, they may be constructed of non-water-proof material, in which case the unit may be dipped in tar or 20 asphalt to render it water-proof.

The insulating unit or slab above described may be manufactured at a comparatively low cost and provides a very practical insulation in the construction of refrigerators and other 25 apparatus of a similar character. It may also be used as an insulation in the construction of walls, floors, ceilings, and roof structures. In practice, the units are manufactured to the required size for a given installation 30 in order to avoid cutting, which would render the unit non-water-proof.

I claim as my invention:

1. An insulating unit comprising a plurality of separate, substantially flat, preferably 35 fibrous sheets arranged in superposed and engaging relation, water-proof caps fitted over the ends of said fibrous sheets to bind them together and to protect said ends from moisture, and a coating of water-proof material applied about the full length of the perimeter of the superposed sheets of said unit between 40 said water-proof caps and in overlapping and sealing relation with said caps.

2. An insulating unit comprising a plurality of separate, substantially flat, preferably 45 fibrous sheets arranged in superposed and engaging relation, water-proof caps fitted over the ends of said fibrous sheets to bind them together and to protect said ends from moisture, and a water-proof casing sheet applied about the full length of the perimeter of the superposed sheets of said unit between said 50 water-proof caps and in overlapping and sealing relation with said caps.

55 3. An insulating unit comprising a plurality of separate, substantially flat, preferably fibrous sheets arranged in superposed relation, water-proof caps of flexible material mounted upon and enclosing the opposite 60 ends of said sheets to bind them together and a water-proof casing sheet applied about the full length of the perimeter of the superposed sheets of said unit between said water-proof caps and in overlapping relation with said 65 caps, the opposite end portions of said casing

sheet being sealed to each of said water-proof caps about the perimeter thereof.

In witness whereof, I have hereunto set my hand this 17th day of September, 1927.

WILLIAM E. NELSON.
